BLOWLAMP

Leopold Levit, Prague, Czechoslovakia

Application July 8, 1936, Serial No. 89,681
In Czechoslovakia July 25, 1935

8 Claims. (Cl. 158—35)

This invention relates to blowlamps of the type comprising a vaporizer for producing the impinging flame, and consists essentially in associating with the vaporizer a heater which likewise produces a stiff flame. In this manner not only is the thermal efficiency of the lamp improved, that is to say the fuel consumption reduced, but the possibility is also provided of using the lamp in any desired position, since the heating flame always remains directed against the vaporizer irrespective of the position of the lamp as a whole. At the same time the heater and the vaporizer can be placed so close to each other that the heating flame does not assume the typical pointed shape of a blow-pipe flame but merely plays round the vaporizer. What is essential to the invention is that there shall be "blown flames" that is to say flames fed by fuel emerging under pressure, and that the nozzles or discharge orifices of the heating device and of the vaporizer shall be facing each other.

Forms of construction embodying the invention are shown, by way of example, in the accompanying drawing which forms part of this specification, and in which:

Fig. 1 shows a blowlamp in accordance with the present invention, in side elevation, and partly in longitudinal section.

Fig. 2 is a view similar to Fig. 1 of a modification; and

Fig. 3 is a fragmentary elevation of a further modification.

Referring to Fig. 1 of the drawing, the heating device comprises a tubular casing forming a heater 1 into which a sleeve 2 is slidably and rotatably fitted. The extent to which this sleeve can be slid into the outer casing or shell is limited by stops 3 provided on the sleeve. Into the sleeve 2 there is inserted a round tubular wick 4 which extends into the lower part of the casing or heater 1. The upper part of the wick 4 is arranged to encase a member 5 having an outlet orifice 6 at the side. This member is preferably in the form of a hollow sleeve closed at the upper end which projects from the end of the wick 4. Into the lower, open end of this member there is inserted the end of a simple or multiple cord wick 7 which is passed through the hollow wick 4. The orificed sleeve member 5 is further provided with a distancing rod 8 which extends through the entire length of the casing or heater 1 and bears against the bottom thereof for the purpose of retaining the member 5 in its correct relative position and preventing the same from becoming forced inwards. The upper end of the cord wick

7 is spaced from the top of the sleeve 5 to provide a vaporizing chamber therein. The adjustability of the sleeve 2 serves to admit of regulating the flame from the wick 4 and of allowing for the burning away of this wick. A cap 35 is provided as a protection for the burner orifice member 5 when not in use.

The second main part of the lamp, the vaporizer, consists of a closed tubular shell formed of the lower part 9 and upper part 10. The upper part 10 is filled with suitable absorbent material 11, for example cotton-wool or cotton-waste, which extends into the lower part 9. This filling is attached by its upper end to a distancing member 12 which bears against the upper end or head 15 of the part 10 of the shell. The head end of the shell is thus kept free from the filling material and constitutes a vaporizing chamber 13. This chamber is provided at the side with an orifice or nozzle 14.

The two tubular shells 1 and 9 are connected together in spaced relation by means of a dual holder 15 in which the shells can be longitudinally displaced relatively to each other to any desired extent and rotated about their own axes. 25 The holder is slideable on both shells, to enable the conducting of heat from the vaporizer shell 9 to the heater shell 1 to be regulated.

The mode of operation of the lamp is as follows:

Fuel (for example spirit) is poured into the shells 1 and 9, and this fuel, after the apparatus is assembled, is absorbed by the two wicks 4 and 7 and by the filling material 11. The fuel vapor proceeding from the wick 4 at the upper end of the sleeve 2 is then ignited. The flame thus maintained heats the vaporizer member 5, with the result that fuel vapor issues under pressure from the orifice 6, becomes ignited by the flame from the wick 4 and forms a stiff flame 19. 40 This auxiliary blown flame impinges against the vaporizing chamber 13 forming part of the shell 9, with the result that rapid vaporization of the fuel in this chamber takes place. The fuel vapor thus generated issues under pressure from the orifice 14 and becomes ignited by the flame 19, 45 thus forming the main or working impinging flame 20. Since the main impinging flame 20 passes through both the wick flame and the auxiliary impinging flame 19 the jet of gas issuing from the orifice or nozzle 14 is always re-ignited if ever the working flame becomes interrupted or extinguished, so that the continuous functioning of the latter is ensured. The main or working flame can be so directed that it partly im- 50 55

pinges against the upper part of the vaporizer member 5, thus intensifying the vaporizing action in this member and consequently increasing the heating of the main vaporizing chamber 13 and thereby producing a stronger working flame. By longitudinal displacement of the shell 9, 10 relatively to the shell 1, the main impinging flame or working flame 20 can be altered in shape, so as to make this flame more spread out or more concentrated, as required. Different effects can likewise be obtained by rotation of the shell 1 so that the heating flame 19 impinges against different parts of the vaporizing chamber 13. If work is to be interrupted, the two shells are turned so that the flames 19 and 20 are approximately parallel to each other, the working flame 20 being thereby extinguished. The described construction of the lamp enables very high temperatures to be obtained with low fuel consumption, the temperature of the working flame produced being sufficient for soldering, brazing, welding, melting, heating, burning off paint, removing the wax from skis, and many other purposes. In addition, the lamp has the advantage that, on account of the stiffness of the flames 19 and 20, it can be used in any position.

It is advisable to make the head piece 10 from material of inferior heat radiating power, that is to say for example from copper, brass, or aluminium, so that the heat supplied to the vaporizing chamber 13 by the heating flame may be utilized to the full in this chamber, with the least possible dissipation. Aluminium is more particularly well suited for this purpose, on account of its ready deformability. I have found that if such material be used it is generally not necessary to taper the vaporizing chamber, since the reduction thereby effected in the heat loss due to radiation is sufficient in itself to ensure rapid and powerful heating up.

The connection or joint between the head 10 and the shell of the vaporizer can be of various types.

On the sleeve 2 (see Fig. 1) there is preferably provided an igniting device 29 which may be permanently or detachably mounted thereon. The apparatus can be mounted on a base 31.

Fig. 2 shows a form of construction in which a number of details are modified. The wick 4 is provided with a braking spring 36 which prevents this wick from slipping in the casing 1, and thereby enables the distancing stem 8 (Fig. 1) to be dispensed with. This spring is formed of a piece of wire which is passed through the wicks 4 and 7, and which bears resiliently against the inner wall of the casing 1; the spring 36 thus also fixes the positions of the wicks 4 and 7 relatively to each other. In order that the wick may not collapse or double up in its length when being disposed of it is made from stiff material or reinforced by having stiffening material incorporated with it.

At the upper end of the wick 7 there is slidably fitted a sleeve 37. On the sleeve 2 telescoped in the casing 1 there is likewise fitted a sleeve 38 which is guided on the outside of the sleeve 2. The telescoped sleeve 38 serves for regulating the flame burning from the wick 4, for which purpose it is pushed down to permit the flame to be lit, after which it is moved upwards to such an extent that it extends beyond the upper edge of the wick 4, so that not the liquid fuel contained in the wick but the fuel vapor above the wick burns. Fine adjustment of this nature can be more readily effected with the sleeve 38 than with the sleeve

2 in the form of construction shown in Fig. 1. The sleeve 37 serves as a guide for upper end of the telescoped sleeve 38. In order to increase the heat of the flame perforations 39 are provided in the sleeve 38 for the admission of air. This is possible because no over pressure exists within the shell 38 except as confined within the shell 5.

In the vaporizer the wick 11 is so disposed that it is a close fit in the upper part thereof, by being quadruply folded, while its lower end, which is 10 immersed in the fuel contained in the lower part 9, can remain loose. The result achieved by this measure is that the fuel drawn up by the wick is more rapidly vaporized by the action of the burner flame, without the power part 9 of the casing 15 becoming hot. The tight fitting or stuffing of the wick 11 in the tapered part 10 of the vaporizer also enables the distancing member 12 (Fig. 1) to be dispensed with. The portion of the wick material 11 extending into the head 10 is surrounded by fine mesh wire gauze 11a. The upper end of the vaporizer shell 9 is reinforced by a ring 40 to stand the strain due to heat and expansion of the head 10.

The main impinging flame or working flame of 25 the blowlamp can be regulated by varying the distance between the vaporizing chambers 5 and 13. For this purpose, in the form of construction shown in Fig. 3 the outer fitting ring 41 carrying the vaporizer 5 of the heater has this vaporizing 30 chamber 5 mounted eccentrically, so that by mere rotation of this ring the clearance between the vaporizing chambers can be varied. The spring 36 prevents the chamber 5 from turning, thereby preventing the auxiliary flame from the vaporizing 35 chamber 5 from missing the chamber 13 as the fitting ring 41 is turned. Thus, the ring 41 merely rotates around the chamber 5 as it moves said chamber about. At the extreme side positions of movement, the flame from the chamber 40 5 barely hits the chamber 13 and the lowest working flames are generated from these positions. With this form of construction the further advantage is obtained that the lamp can be tilted to a greater extent without causing fuel to 45 flow out.

I claim:

1. A blowlamp including a fuel tank and an orificed vaporizing chamber, at least one heater for said chamber, said heater including a tubular casing comprising a fuel receptacle, means connecting said casing to said blowlamp in spaced relation thereto, a sleeve slidably and rotatably fitted on the upper end of said casing and providing an extension thereof, means limiting the sliding movement of said sleeve in one direction, a tubular wick carried within said casing and having its upper end normally extending beyond the upper edge of said sleeve, a tubular member having a closed upper end carried by said wick inwardly thereof, the upper end of said member extending above the upper end of said wick, the upper end of said member being formed to provide an orifice therein facing said blowlamp, a second wick carried within said member, the upper end of said second wick terminating short of said closed end of said member to provide a vaporizing space therein, whereby heat from said first wick heats said last named chamber to cause vaporized fuel to be expelled through said orifice under pressure, thereby creating a blow-pipe type of flame directed against the vaporizing chamber of said lamp to heat the same.

2. The structure of claim 1, said vaporizing chamber of said lamp being formed to provide 75

- an outlet orifice at the side, said heater comprising a sleeve closed at the head end and being formed to provide an outlet orifice at the side, a wick for supplying fuel to the said sleeve, a hose wick for heating said sleeve, the sleeve being formed to provide a flame outlet orifice in the side thereof facing said orifice of said lamp so that the blowlamp flame crosses the flame of the heater and the flame of the hose wick.
5. A blowlamp as claimed in claim 1, said heater comprising a vaporizing sleeve, a fuel feeding cord wick extending up into the said sleeve, a hose wick around the said cord wick and part of said vaporizing sleeve, a tubular shell and slid-
20 able thereon to regulate the flame thereof encas-
ing said wicks and sleeve, and an outer sleeve fitted over the upper end of the said hose wick.
5. A blowlamp as claimed in claim 1, said heater comprising a vaporizing sleeve, a fuel feeding cord wick extending up into the said sleeve, a hose wick around the said cord wick and part of said vaporizing sleeve, a tubular shell encasing said wicks and sleeve, and a braking spring associated with the said wicks and adapt-
30 ed to bear against the inner wall of the said shell to maintain said wicks in the same relative positions.
6. A blowlamp as claimed in claim 1, said portion of said casing of said heater comprising a plurality of sleeves rotatably fitting one within the other, said sleeves being adjustable relatively to each other, a wick for said heater, said sleeves being arranged in vertically disposed relation, the upper portion of the topmost sleeve being dis-
40 posed eccentrically to the lower portion thereof, said lower portion fitting within the next sleeve below, said upper end of the topmost sleeve surrounding and supporting said wick.
7. A blowlamp including a fuel tank and an orificed vaporizing chamber, at least one heater for said chamber, said heater including a tubular casing comprising a fuel receptacle, means connecting said casing to said blowlamp in spaced relation thereto, a sleeve fitted on the upper end
45 of said casing and providing an extension thereof, a tubular wick carried within said casing and having its upper end normally extending beyond the upper edge of said sleeve, a tubular member having a closed upper end carried by said wick, inwardly thereof, the upper end of said member extending above the upper end of said wick, the upper end of said member being formed to provide an orifice therein facing said blowlamp, a second wick carried within said member, the upper end of said second wick terminating short of said closed end of said member to provide a vaporizing space therein, whereby heat from said first wick heats said last named chamber to cause vaporized fuel to be expelled through said orifice under pressure, thereby creating a blow-pipe type of flame directed against the vaporizing chamber of said lamp to heat the same.
8. A blowlamp including a fuel tank and an orificed vaporizing chamber, at least one heater for said chamber, said heater including a tubular casing comprising a fuel receptacle, means connecting said casing to said blowlamp in spaced relation thereto, a sleeve slidably and rotatably fitted on the upper end of said casing and providing an extension thereof, means limiting the sliding movement of said sleeve in one direction, a tubular wick carried within said casing and having its upper end normally extending beyond the upper edge of said sleeve, a tubular member having a closed upper end carried by said wick inwardly thereof, the upper end of said member extending above the upper end of said wick, the upper end of said member being formed to provide an orifice therein facing said blowlamp, a second wick carried within said member, the upper end of said second wick terminating short of said closed end of said member to provide a vaporizing space therein, whereby heat from said first wick heats said last named chamber to cause vaporized fuel to be expelled through said orifice under pressure, thereby creating a blow-pipe type of flame directed against the vaporizing chamber of said lamp to heat the same, the upper end of said sleeve having a sliding fit on said tubular wick, said sleeve comprising means for regulating the flame of said tubular wick.

LEOPOLD LEVIT.
